LIQUID DISCHARGE SYSTEM

Charles H. Lindsay, Elmira, N. Y., assignor to
 American-La France-Foamite Corporation,
 Elmira, N. Y., a corporation of New York

Application August 2, 1941, Serial No. 405,171

7 Claims. (Cl. 169—9)

The invention relates to liquid discharge systems for pressure containers such as the fire extinguishing flasks of carbon dioxide and like extinguishing media. Its principal object is to provide such a flask with a dip-tube structure adapting it for reliably discharging liquid in preference to vapor in all positions of the flask, and in such form and novel design as to permit such structure to be applied to and supported by the operating head of the flask so as to be removable with the latter through the narrow neck opening of the flask.

To this end the invention comprises an organization of concentric shells and coaxial valve ports and gravity valve mechanism according to the principle illustrated in the accompanying drawing wherein:

Fig. 1 represents a conventional flask having the invention applied and Fig. 2 is a larger scale section through the intake structure.

The operating head 1 of conventional form is shown on a conventional flask and may be understood to contain a sealing disc which is punctured when the contents of the flask are to be delivered. Such head is screwed into the neck opening 2 of the flask and the dip-tube structure about to be described is mounted on the inner end of the head, or so as to be removable when the head has been removed.

This structure includes a flexible intake section 3 provided with a weight bob at its far end and a coupling member 4 by which such flexible section is mechanically attached to the head. The intake section is flexible in order that its lower end will drop into the liquid in the lower part of the flask when the latter is in inclined positions, but instead of being itself flexible it could be rigid and connected to the coupling member 4 by a ball joint as sometimes used in this art. As shown, it is connected by solder.

The coupling member 4 is constituted of a main cylindrical shell or casing 4 of a diameter no greater than that of the neck opening so that it can pass through it and all of the flow controlling elements are housed within this casing. It is attached to the head in any appropriate way, in the present case by being screwed on to the stem 5 of a cylindrical shell 6 coaxially located within the shell 4, which stem 5 in this case is screwed into the head, thus forming the connection.

The end of the shell 4 that is attached to the intake section 3 is provided with a valve chamber formed with a valve port 8 and containing an associated ball valve 9. The valve port may be

formed on the shell 4 but is indicated as carried on an inserted element; either way suffices.

The annular space between the concentric shells 4 and 6 constitutes a chamber which is in permanent communication with the operating head by way of the ducts 10 bored in the stem 5, and the chamber represented by the space inside the inner shell 6 is in permanent communication with the flask space near the head end of the flask, through a ring of eyelet tubes 11. The cross area of the annular chamber, between shells 4 and 6, and the aggregate area of the cross ducts 10, each equals or exceeds the area of the passageway through the operating head, and similarly the aggregate areas of the eyelet tubes 11 approximate or exceed that same passageway, so that no point of constriction to the flow occurs in the construction described.

The central chamber 6 communicates with the annular chamber of shell 4 through a valve port 12 formed on the lower end of the shell 6 and provided with an associated ball valve 13 which can roll in this shell to a position below the eyelet tubes 11, when the flask is inclined past horizontal.

Each of the ports 8 and 12, as can be seen, also provides a flow-way at least as large as the discharge passageway through the operating head. These ports are coaxial and proximate, and loosely confined between them is a floating spacer 14 so dimensioned that when the ball of one port moves to its seat the spacer pushes the other ball off its seat, in case it should adhere to it for any cause, thus assuring that one or the other of said ports will always be open. Normally, with flask erect, the spacer rests on top of the valve port 8; it is shown in midway position to indicate its floating character.

In operation, with the flask erect as shown, valve 13 is closed and the port 8 is opened so that on opening the discharge head, liquid from the lower part of the flask may flow upwardly through the intake section 3 past ball 9, through the annular chamber of shell 4 and ducts 10 into and out of the head, escape of vapor being prevented by the closure of valve 13. When the flask is inverted, or in a position inclined to or more than 90° from vertical, the valve mechanism is reversed, port 8 being then closed and port 12 open, so that liquid from the then bottom part of the flask, enters through the eyelet tubes 11 into inner or central chamber 6 and thence flows by outer annular chamber 4 to and through the operating head, vapor escape in this case being prevented by closed valve 9. In neither

case does the coupling structure oppose any greater restriction to flow than is found in the operating head itself, which fact is important for carbon dioxide systems in particular because restriction leads to expansion, cooling and freezing of the liquid, preventing its prompt discharge.

I claim:

1. In a liquid discharge system a container or flask, an operating head adapted to be removably screwed into the neck opening thereof and a dip-tube structure within the flask including a movable intake section extending toward the opposite end of the flask and a coupling member connecting such section to the outlet passage in the head, such coupling member containing concentric chambers, means providing a permanently open communication from one of said chambers to the operating head, means providing a permanently open communication from another of said chambers to the flask space adjacent the head, a port connecting said chambers with each other and a port connecting one of said chambers with said intake section, and gravity valve mechanism for alternately closing said ports according to the position of the flask.

2. In a liquid discharge system a gas flask, an operating head screwed into the neck opening thereof and a dip-tube structure supported on such head within the flask and including a movable intake section extending toward the opposite end of the flask and a coupling member mechanically connecting such section to the head, such coupling member comprising a cylindrical casing and an inner shell therein forming two coaxial chambers, one of said chambers being in permanent communication with the operating head and the other with the flask space adjacent the head, a port connecting said chambers with each other, another port connecting one of said chambers with said intake section, and gravity valve mechanism for alternately closing said ports according to the position of the flask.

3. In a liquid discharge system, a gas flask, an operating head secured in the neck-opening thereof, a dip-tube structure within the flask including a movable intake section extending toward the opposite end of the flask and a coupling member connecting such section to the head, such coupling member comprising a casing adapted to pass through said neck-opening and containing two coaxial chambers, means providing a permanently open communication from one of said chambers to the operating head, means providing a permanently open communication from the other chamber to the flask space adjacent the head, a port forming a communication between said chambers, another port connecting one of said chambers with said intake section and gravity valve mechanism in said casing for alternately closing said ports according to the flask position.

4. In a liquid discharge system a gas flask, an operating head therefor and a dip-tube structure supported within the flask including a mov-

able intake section extending toward the opposite end of the flask and a coupling member between such section and the head, such coupling member comprising a cylindrical casing containing a concentric shell and therewith forming two chambers, one of said chambers being in permanently open communication with the operating head, and the other being in permanently open communication with the flask space adjacent the head, a port connecting said chambers with each other, a second port connecting one of said chambers with said intake section, and gravity valve mechanism for alternately closing said ports according to flask position.

5. In a liquid discharge system a gas flask, an operating head screwed into the neck opening thereof and a dip-tube structure within the flask connected with such head and including an intake section extending toward the opposite end of the flask and a coupling member connecting such section with the head, such coupling member containing a wall forming concentric chambers in permanently open communication with the operating head and the flask space adjacent the head, respectively, the interior chamber having a port in said wall for connecting it with the outer chamber and said intake section having a port connecting it with said outer chamber, said ports being coaxial and proximate to each other, and gravity valve mechanism for alternately closing said ports according to the flask position.

6. In a liquid discharge system a flask, a dip-tube structure therein including an intake section and a cylindrical casing forming the connection therefor to the outlet of the flask, an inner shell in said casing forming concentric chambers therein, the outer chamber having connection with the flask outlet and the inner chamber having one or more eyelet tubes, crossing through the outer chamber, connecting it with the flask space exterior of said casing and gravity valve mechanism controlling the flow through said intake section and chambers.

45 7. In a liquid discharge system, a pressure flask having a discharge head in its neck opening and a dip-tube structure connected with the head comprising an intake section and a cylindrical casing forming the connection between said intake section and the discharge head, said casing comprising internal wall structure containing two adjacent coaxial ports and ball valve mechanism controlling such ports, the outlet sides of said ports being in permanent communication with the outlet passage through said neck opening and the inlet sides of said ports being in communication, respectively, with said intake section and the space in the flask adjacent said discharge head.

CHARLES H. LINDSAY.
